(57) **CLAIM**

The ornamental design for a lamp, as shown and described.

DESCRIPTION

FIG. 1 is a front, right and top perspective view of a lamp, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1; and,

FIG. 10 is an enlarged view of detail 10 in FIG. 2.

The broken lines depict portions of the lamp that form no part of the claimed design.

The dot-dash broken lines in FIGS. 1, 2, 9 and 10 depict the boundaries of the enlargements that form no part of the claimed design.

The lamp is shown with symbolic break lines in its length and the appearance of any portion of the lamp between the pairs of dot-dot-dash break lines forms no part of the claimed design.
